UNITED STATES PATENT OFFICE

WILLIAM C. DEVEREAUX, OF DETROIT, MICHIGAN

DOORLATCH CONSTRUCTION

Application filed October 28, 1931. Serial No. 571,223.

This invention relates generally to door latch constructions and refers more particularly to the outside handle and rollback assemblies of vehicle door latches.

5 One of the essential objects of the invention is to provide an assembly of this type wherein means is provided for taking up play between the rollback and handle stem and for holding the stem and handle in a predetermined position when the parts are 10 installed on the vehicle door.

Another object is to provide an assembly which can be economically manufactured and easily and quickly installed.

15 Other objects, advantages and novel details of construction of this invention will be made more apparent as this description proceeds, especially when considered in connection with the accompanying drawing, 20 wherein:

Figure 1 is a fragmentary elevation of a vehicle door with latch mechanism embodying my invention applied thereto;

Figure 2 is a sectional view taken on the 25 line 2—2 of Figure 1;

Figure 3 is a detail view of one of the rollback sections;

Figure 4 is an edge elevation of another of the rollback sections;

30 Figure 5 is a front elevation of the section illustrated in Figure 4.

Referring now to the drawing, 1 is a vehicle door; 2 is a latch case plate secured to the inner side of the door and having a 35 lateral flange 3 at its forward edge secured to the free edge of the door; 4 is a latch bolt extending through an opening in the flange 3 for engagement with a suitable keeper (not shown) and having a shank 5 slidably mounted on the case plate 2; 6 is a spring anchored on the case plate and having an arm 7 engaging the shank 5 and normally holding the bolt 4 in projected position. 8 is a cover plate arranged in spaced relation to the case

40 plate 2 and rigidly secured thereto and to the flange 3; 9 is a handle operable from the outer side of the door and having a stem 10 of substantially square cross section disposed substantially parallel to the lateral flange 3 of the case plate, and 11 is a sec-

tional rollback on the stem 10 between the plates 8 and 2 and operable by the stem and handle to effect a retraction of the bolt 4 against the tension of the spring 6.

In the present instance the rollback 11 55 comprises three sections A, B and C respectively arranged side by side on the stem 10. Preferably the sections A and C are similar and are formed from relatively heavy gage sheet metal. As shown, these sections have 60 circular recesses 14 and 15 respectively opposing each other and forming a central chamber D and have laterally projecting circular hub portions 16 and 17 respectively in alignment with said recesses 14 and 15 and journaled in aligned openings 18 and 19 respectively in the plates 2 and 8. The sections A and C also have overlapping upstanding complementary arm portions 20 and 21 respectively that are normally engaged by a shoulder 22 of the spring pressed bolt shank 5 and are held thereby against the lateral flange 3 of the case plate. In this connection it will be noted that the arm portions 20 and 21 are in alignment when the 65 stem receiving openings 23 and 24 therein are in registration. The section B is circular and fits snugly within the chamber D formed by the opposed recesses 14 and 15. Preferably this section B is formed from 70 light gage spring metal and is provided at one side with a vertical web 25 having a substantially square opening 26 receiving the stem 10 and having four lugs 27 inclining 75 from the edges of the square opening 26 and yieldably engaging the four sides of the stem 10. The section B is also provided at substantially diametrically opposite points thereof with substantially rectangular-shaped notches 30 and 31 respectively that 80 receive correspondingly shaped lugs 32 and 33 respectively at diametrically opposite points of the recess 15.

In use the lugs 32 and 33 constitute steps 85 for holding the section B in correct relation to the sections A and C, and the lugs 27 are under tension and bear firmly against the stem 10 of the handle, hence when the shoulder 22 of the spring pressed bolt shank 5 bears against the arm portions 20 and 21 of 100

the sections A and C the intermediate section B will take up any play between the sections and stem and the latter and the handle 9 will be held in a horizontal position.

5. What I claim as my invention is:

1. In a door latch, a rollback having a section of substantially circular formation provided with a web having a substantially square opening for receiving a handle stem, 10 and lugs extending from the edges of the opening for bearing engagement with the sides of the stem, and complementary sections having opposed recesses receiving the section aforesaid and having aligned arms for engagement with a bolt shank, one of the last mentioned sections having an interlocking engagement with the first mentioned section.

2. In a door latch, a case plate having a lateral flange, a handle having a stem substantially parallel to said flange, a spring pressed bolt shank on the plate and urged toward said flange, and means for holding the handle and stem in a predetermined position relative to the case plate including a 25 rollback having sections arranged side by side on said stem between the flange and shank, one of said sections being formed of relatively light gage spring metal non-rotatably secured to another of said sections and 30 having a yieldable portion bearing against said stem.

3. In a door latch, a rollback having three sections, two of said sections being similar and having complementary arms for engagement with a latch bolt, said similar sections also having opposed recesses forming a chamber, and the third section being wholly within said chamber, interlocked with one of the two sections aforesaid and having yieldable 40 means engageable with a handle stem.

4. In a door latch, a rollback having three sections arranged side by side, two of said sections being similar, one of said similar sections and the third section having interlocking engagement with each other, and the third section being enclosed by the similar sections and having a yieldable portion for bearing engagement with a handle stem.

5. In a door latch, a rollback including 50 three sections arranged side by side having aligned openings for receiving a stem of a latch handle, two of said sections being similar, and the third section being between and enclosed by said similar sections and having 55 yieldable means engageable with the stem aforesaid.

6. In a door latch, a rollback including 60 three sections arranged side by side and having aligned openings therein for receiving a stem of a latch handle, two of said sections being similar, a separable connection between one of said similar sections and the third section holding the third section in correct relation to the similar sections, said similar sections having overlapping complementary 65

arms for engagement with a flange of a case plate and with a shoulder of a latch bolt respectively, and means for taking up play between the sections and the stem when the arms are in engagement with the shoulder, including 70 spring tongues projecting from the third section for engagement with the stem of the latch handle.

7. In a door latch, a rollback having three sections arranged side by side, two of 75 said sections being similar and formed of relatively heavy gage metal, said similar section having aligned openings for receiving the stem of a latch handle and having circular recesses opposing each other and forming 80 a central chamber, said sections also having laterally projecting hub portions and having overlapping complementary arm portions, the third section being circular in configuration and fitting within the chamber 85 aforesaid, said third section being formed from relatively light gage spring metal and provided at one side with a vertical web having an opening in alignment with the openings aforesaid and having lugs inclining from 90 the edges of the opening in the web for yieldably engaging the sides of the handle stem.

8. In a door latch, a rollback including 95 three sections arranged side by side, two of said sections being similar and having aligned openings therein for receiving the stem of a latch handle, said similar sections having opposed recesses forming a central 100 chamber and having overlapping complementary arm portions, the third section being substantially circular in configuration and fitting within the chamber aforesaid, said third section being provided at one side with a vertical web having an opening in alignment 105 with the openings aforesaid and having lugs inclining from the edges of the opening for yieldable engagement with the sides of the stem.

9. In a door latch, a rollback including 110 three sections arranged side by side, two of said sections being similar and having aligned openings for receiving the stem of a latch handle, the third section being enveloped by 115 said similar sections and having a web provided with an opening in alignment with the openings aforesaid, lugs projecting from the edges of the opening in the web for yieldable engagement with the sides of the stem, and said third section also being provided with notches, and lugs projecting from one of the 120 similar sections aforesaid and engaging said notches whereby the third section will have an interlocking engagement with one of the similar sections.

10. In a door latch, a rollback having two 125 sections arranged side by side and having arm portions for engagement with a bolt shank, said sections having aligned openings for receiving the stem of a latch handle and provided about said openings with opposed 130

recesses forming a chamber, and means within said chamber interlocked with one of said sections and having means for engaging the handle stem whereby play between the sections and stem will be taken up and the stem and handle will be held in a predetermined position.

11. In a door latch, a rollback having three sections, two of said sections having arm portions for engagement with a bolt shank and being arranged side by side and free from each other, said two sections having aligned openings for receiving the stem of a latch handle and provided about said openings with opposed recesses forming a chamber, and the third section being within said chamber in interlocked relation to one of said sections and having means for engagement with the handle stem.

12. In a door latch, a rollback having outer and inner sections, the outer sections having projecting arm portions for engagement with a bolt shank and having aligned openings for receiving a handle stem, said outer sections being provided about said openings with opposed recesses forming a chamber, and the inner section being wholly within said chamber between portions of said outer sections, interlocked with one of said portions, and having means for engaging the handle stem that is received in the aligned openings aforesaid in the outer sections.

13. In a door latch, a rollback having a section for engagement with a handle stem and having two sections provided at opposite sides of and in alignment with the first section with openings for receiving a handle stem, said two sections having engaging flat faces about and provided with opposed recesses that receive and enclose the first section, said two sections having projecting arm portions for engagement with a bolt shank, and one of said two sections being interlocked with the first mentioned sections.

14. In a door latch, a handle stem, a rollback on the stem, and means for taking up play between the rollback and stem including a member surrounding and having yieldable means cooperating with the stem and having other means connected to the rollback.

15. In a door latch, a handle stem, a rollback on the stem, and means for taking up play between the rollback and stem, including a member having yieldable means pressing against the stem and under tension and having other means interlocked with the rollback.

16. In a door latch, a handle stem, a rollback on the stem, and means for taking up play between the rollback and stem, including a member having an opening receiving the stem and lugs under tension pressing against the stem, and having other portions interlocked with said rollback.

17. In a door latch, a handle stem, a rollback on the stem, and means for taking up play between the rollback and stem including a member having parts respectively receiving the stem and under tension and in engagement therewith, and having other parts respectively at one side and interlocked with portions of the rollback.

In testimony whereof I affix my signature.

WILLIAM C. DEVEREAUX.
